(57) **CLAIM**

The ornamental design for a handle, as shown and described.

DESCRIPTION

FIG. 1 is a front perspective view of a handle showing my new design;

FIG. 2 is a top plan view thereof, the bottom plan view is a mirror image of the top plan view;

FIG. 3 is a rear view thereof;

FIG. 4 is a front view thereof; and,

FIG. 5 is a right view thereof, the left view is a mirror image of the right view.

The broken lines are included for the purpose of illustrating portions of the handle that form no part of the claimed design.
